The ornamental design for a scanner, as shown and described.

DESCRIPTION

FIG. 1 is a perspective view of a scanner showing our new design;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view showing the scanner with the catch tray closed; and,

FIG. 9 is a perspective view showing the scanner with the guides extended from the shoot and catch tray.

The broken lines in the drawings are for the purpose of illustrating unclaimed portions of the scanner and form no part of the claimed design.

1 Claim, 6 Drawing Sheets(58) **Field of Classification Search**
